UNITED STATES PATENT OFFICE.

JACOB H. KAPLAN, OF CHICAGO, ILLINOIS.

APPARATUS FOR APPLYING HEAT AND AIR IN DENTAL WORK.

Application filed December 17, 1925. Serial No. 75,970.

It is well known that in dentistry it is necessary to resort to the application of heat and air, the heat generally being supplied by means of a gas or alcohol flame while the air 5 has usually been supplied by being blown from a pipe one end of which is placed in the mouth of the operator.

While some good results have been obtained in this manner it has been found that many 10 objections and difficulties present themselves, especially with work which is of such a nature that all of the attention of the operator is required upon the work.

In the use of modeling or impression 15 compound and in other instances it is sometimes desirable or necessary to employ an intermittent blast and at other times a constant or continuous blast is necessary, according to the nature of the work.

20 With the present methods it necessitates considerable experience before one can become expert in controlling such blast to produce the desired heat, when a flame is used, and to control and localize the heat. Often- 25 times, especially when the application of a continuous blast of heat is required, the work is spoiled by reason of the fact that the operator must "catch" his breath to continue the operation of blowing.

30 Furthermore the blast will be uncertain and irregular as the proper amount of air will not be supplied in proportion to the flame, resulting in the production of a flame which is too hot, which injures or reduces the work- 35 ing qualities of the impression material con-sequently the quality of the work as it is im-possible to regulate the blast with the appli-cation of air blown from the mouth of the operator, all of which is disconcerting and 40 imposes upon the operator an extra task of watching and trying to control the flame.

In chip blowing or in the application of a liquid cleansing compound, suction is very objectionable in that the impurities are rede- 45 livered back to the work or field of operation.

Other apparatus have been designed for this class of work but they have been of a large and unwieldy nature rendering it difficult and cumbersome for the operator to han- 50 dle or manipulate the same.

It is one of the objects of the present inven-

tion to overcome these and many other ob- 55 jections and difficulties encountered in the methods and apparatus now employed, and to provide in an improved apparatus for apply- 60 ing a blast of heat or of fluid, means whereby it is possible to secure a sustained or an in- 65 termittent blast at the election of the opera- 70 tor, suitable for use in dental work of any na- 75 ture where such a blast is necessary or desir- 80 able, and which apparatus will be of a com- 85 pact construction and arrangement easily to 90 be handled and which will also be effective 95 and efficient in operation.

A further object is to provide in an appa- 65 ratus of this character improved means 70 whereby a supply of fluid for cleansing or for 75 other operations may be produced without 80 danger of regurgitation.

A still further object is to provide an im- 70 proved hand apparatus of this character 75 including means whereby a sustained blast 80 may be produced in places where desired and 85 where the convenience of fluid pressure creat- 90 ing apparatus is not available, thereby pro- 95 viding all of the conveniences of work with 100 a fluid pressure, without involving the neces- 105 sity of installing an expensive fluid pressure 110 creating apparatus.

To the attainment of these ends and the ac- 80 complishment of other new and useful objects 85 as will appear, the invention consists in the 90 features of novelty in substantially the con- 95 struction, combination and arrangement of 100 the several parts, hereinafter more fully de- 105 scribed and claimed and shown in the accom- 110 panying drawings illustrating this invention 115 and in which;

Figure 1 is an elevation of a chip blowing 90 apparatus arranged so as to produce either an 95 intermittent or sustained blast.

Figure 2 is an enlarged detail sectional 95 view taken on line 15—15, Figure 1.

Figure 3 is a view of a hand apparatus used 95 in connection with a burner of another type 95 arranged to produce either an intermittent 100 or sustained blast.

Figure 4 is a view in elevation showing 100 another form of apparatus of this character 105 arranged to produce either a sustained or an 110 intermittent blast.

Figure 5 is a top plan view of a "Bunsen"

- burner used in connection with this apparatus, showing a means of dividing the fuel supply to permit other attachments to be used in connection with the burner.
- 5 Referring more particularly to the drawings and to the form of the invention shown in Figure 4, the numeral 20 designates an inflatable and deflatable bulb-like device to which is connected a nozzle 21.
- 10 Leading from the bulb 20 is a fluid (such as air) supply pipe 22 and through which pipe the fluid is discharged when the bulb is deflated.
- The bulb in this form of the invention is 15 preferably mounted upon a supporting base 23 having a tubular upright 24 which has communication with the inside of the bulb 20. An inlet 25 is provided for supplying fluid to the bulb.
- 20 A fuel pipe 26 is provided which discharges into the nozzle 21 and connected with this fuel pipe is a flexible supply pipe 27 which receives its fuel supply from any suitable source (not shown).
- 25 A burner 28 preferably of the "Bunsen" type is provided for use in connection with the apparatus and the burner (see particularly Figure 5), is provided with an inlet pipe 29 to which is connected a supply pipe 30. The pipe 29 is provided with a valve 31 for controlling the supply of fuel to the burner, and the pipe 29 is provided with branches 32, 33 respectively provided therein with valves 34, 35.
- 35 The pipe 27 is preferably connected to one of the extensions or branches of the pipe 29, such as the branch 32, so that the burner 28 may be used at the same time that the nozzle 21 is being used, without interfering with the 40 operation of one with respect to the other.
- In use the valve 34 is opened so as to supply fuel to the pipe 26 and the fuel is ignited at the end of the nozzle 21.
- 45 By manipulating the nozzle the flame may be directed against any part of the work to be operated upon, and by deflating the bulb 20 and allowing the same to be inflated, there will be an intermittent blast of fluid discharged through the pipe 22 against the flame.
- 50 An additional bulb-like member 38 is interposed between the bulb-like member 20 and the nozzle 21 and pipe 26 for the purpose of producing a sustained blast of fluid so as to provide a sustained blast against the work.
- 55 The pipe 22 has communication with the interior of the bulb-like member 38, and these two devices will constitute fluid chambers having communication with each other through a connection 39.
- 60 The chambers 20 and 38 (see particularly Figure 2) are each provided with an inlet port 40 through which the fluid enters the chamber and communicating with this port and disposed within the chamber 20, is a
- tubular member 41 having a valve 42 disposed therein, and which valve co-operates with a seat 43. Another tubular member 44 is arranged within the chamber 20 and projects through the opposite end of the bulb to form a connection 39 between the chambers. The member 44 telescopes with the member 41 and may be secured thereto in any suitable manner such as by means of screw threads 46. The end of the tubular member 44 serves as a means for preventing displacement of the valve 40.
- The tubular member 44 is provided with openings 47 to permit the fluid which is drawn into the chamber through the inlet 40 when the chamber is inflated, to be discharged into the tubular member 44 and out of the outlet 45, when the wall of the chamber is compressed to deflate the same.
- As shown in Figure 2 the chambers 20 and 38 are coupled together by inserting the connection 39 of the chamber 20 into the inlet opening 40 of the chamber 38.
- The extremity 48 of the tubular member 44 of the chamber 38 which projects beyond the chamber, telescopes into the end of the pipe 22.
- With this arrangement the bulb-like device 20 is adapted to be deflated and inflated to discharge the fluid therefrom into the chamber 38 and when inflated will draw fluid through the inlet 40. The valve 42 in the chamber 20 is seated when the chamber walls are compressed to deflate the chamber and unseated to permit inflation of the chamber 20.
- The valve 42 in the chamber 38 operates in the same manner.
- It will therefore be seen that by inflating and deflating the chamber 20 by compressing the walls of the chamber with the hand and then releasing the same, a pumping action will be produced which will pump the fluid into the chamber 38 causing the latter to serve as a reservoir from which the fluid will flow into the pipe 22 with a continuous and steady flow.
- Should it be desired, however, to produce for any interval of time an intermittent flame, the operator may simply grasp the chamber 38 and impart a pumping action to the chamber wall. A ball like projection 56 may be provided and carried by the base 57 for holding the apparatus steady.
- In Figure 3 there is shown an arrangement of apparatus embodying the bulb-like chambers 20 and 38 which are superposed in the same manner as in Figure 4, but in this form of the invention, the flame is produced from an alcohol lamp 82. The lamp may be supported by means of a suitable tubular projection 83, carried by the chamber 38, preferably by the end 48 of the tubular member 44 of the bulb or chamber 38 telescoping into

such extension. Leading from the extension 83 is a pipe 84 which terminates in a nozzle 85 arranged to direct this blast against the flame 86 sustained by means of a wick carried by the tube 87.

The lamp may be provided with a ball-like projection 88 with which a suitable clamp co-operates to hold the lamp in a fixed position.

10 The operation of this form of the invention is the same as the form shown in Figure 4, that is, by manipulating the bulb-like chamber 20, fluid will be supplied to the chamber 38, which latter forms a reservoir, 15 and the fluid will pass through the chamber into and through the pipe 84 to the nozzle 85 to be discharged against the flame 86.

In Figure 1 there is shown a form of the apparatus for chip blowing or for washing 20 or cleansing work, by directing a blast of fluid against the work, either intermittently or continuously, and when used as such, the arrangement of the parts as shown will prevent drawing the fluid back by suction.

25 In this arrangement the chambers 20 and 38 are superposed and connected with the base 23 in the same manner as shown in Figures 3 and 4 and the nozzle 91 is preferably provided with a removable needle 92 connected 30 thereto for producing a fine stream.

By deflating and inflating the chamber 20 the fluid will be supplied to the reservoir chamber 38 and from there through the pipe 93 to the nozzle in a steady stream. If desired and by manipulating the chamber 38 an intermittent stream will be produced.

With the form of the invention shown in Figure 1 the operator may, if desired, heat the nozzle 91 by means of the burner 28, so 40 as to raise the temperature of the fluid being discharged from the nozzle.

With this invention it will be manifest that there is produced an apparatus for dental work and for analogous uses which will 45 be universal in this nature in that it is adapted, especially in dentistry, to all of the uses for which such an apparatus is employed in such a profession. Furthermore the apparatus will be of a compact nature and will be 50 of a size that it may be readily handled and can be operated without the necessity of detracting the attention of the operator from his work. The collapsible and inflatable bulb serves as a handle for holding the apparatus 55 and at the same time the bulb may be deflated and inflated so that only one hand of the operator is necessary for holding the apparatus and for deflating the hub.

While the preferred form of the invention 60 has been herein shown and described, it is to be understood that various changes may be made in the details of construction and in the combination and arrangement of the several parts, within the scope of the claims,

without departing from the spirit of this invention. 65

What is claimed as new is:

1. A prosthetic lamp embodying means for sustaining a flame, a nozzle disposed adjacent the end of the flame sustaining means, 70 means for supplying a sustained flow of fluid under pressure to the nozzle, the last said means including two inflatable and deflatable fluid receiving chambers having communication with each other, valve mechanism for controlling the passage of the fluid from one of the chambers to the other chamber, one of said chambers serving as a reservoir for compressed fluid supplied thereto by deflating the other chamber, and rigid means forming a 75 connection between the said inflatable and deflatable chambers for maintaining them against bodily deflection one with respect to the other and for supporting one of said chambers above the other and whereby one 80 of said chambers will serve as a handle to bodily lift the lamp and hold the same supported in position for use by the same hand of the operator which collapses the chamber. 85

2. A prosthetic lamp embodying means for sustaining a flame, a nozzle disposed adjacent the end of the flame sustaining means, 90 means for supplying a sustained flow of fluid under pressure to the nozzle, the last said means including two inflatable and deflatable 95 fluid receiving chambers having communication with each other, valve mechanism for controlling the passage of the fluid from one of the chambers to the other chamber, one of said chambers serving as a reservoir for 100 compressed fluid supplied thereto by deflating the other chamber, rigid means forming a connection between the said inflatable and deflatable chambers for maintaining them against bodily deflection one with respect to 105 the other and for supporting one of said chambers above the other and whereby one of said chambers will serve as a handle to bodily lift the lamp and hold the same supported in position for use by the same hand of the 110 operator which collapses the chamber, and a supporting base upon which the said chambers are mounted.

3. A prosthetic lamp embodying means for sustaining a flame, a nozzle disposed adjacent the end of the flame sustaining means, 115 means for supplying a sustained flow of fluid under pressure to the nozzle, the last said means including two inflatable and deflatable fluid receiving chambers having communication with each other, valve mechanism for controlling the passage of the fluid from one of the chambers to the other chamber, one of said chambers serving as a reservoir for 120 compressed fluid supplied thereto by deflating the other chamber, rigid means forming a connection between the said inflatable and deflatable chambers for maintaining them 125

against bodily deflection one with respect to the other and for supporting one of said chambers above the other and whereby either one of said chambers will serve as a handle 5 to lift the lamp and hold it in position for use by the same hand of the operator which collapses the chamber, and a supporting base

upon which both chambers are mounted, said base maintaining the chambers in an upright position and superposed.

10

In testimony whereof I have signed my name to this specification, on this 16th day of December, A. D. 1925.

JACOB H. KAPLAN.
